UNITED STATES PATENT OFFICE.

WILLIAM AUGUST KAGELMACHER, JR., OF JOHNSTOWN, PENNSYLVANIA.

DRILLING-MACHINE.

SPECIFICATION forming part of Letters Patent No. 746,521, dated December 8, 1903.

Application filed February 28, 1903. Serial No. 145,469. (No model.)

To all whom it may concern:

Be it known that I, WILLIAM AUGUST KAGELMACHER, Jr., residing at Johnstown, in the county of Cambria and State of Pennsylvania, have invented certain new and useful Improvements in Drilling-Machines, of which the following is a specification.

This invention relates to drilling-machines; and it consists of a peculiar machine of that character involving novel and improved details of construction for drilling holes in shafting-rods and other places without removing the work from its fixed position. More definitely stated, the invention involves peculiar and novel means for securing the machine and drilling holes regardless of the angle or position thereof.

The invention comprehends improved means for supporting any common drill adapted to the purpose; but it is specially intended for supporting portable pneumatic drilling-tools that are well known and now used.

In order to enable others to make and use my invention, I will now proceed to describe it in detail with reference to the accompanying drawings, forming a part of this specification.

In the drawings, Figure 1 is a view showing my invention in side elevation and part broken away. Fig. 2 is a detail top plan view of the drill-tool-supporting beam. Fig. 3 is a view looking down on the angular base members and with the vertical post providing support for the drill-tool-supporting beam in section, taken on line xx of Fig. 1. Fig. 4 is a detail end view of the base members and sliding block and also showing part of the vertical post. Fig. 5 is a detail end view of the base members arranged upon a circular tube shaft or bolt. The view also illustrates one of my peculiar clamps for holding the work while being drilled. Fig. 6 is a transverse sectional view through the drill-tool-supporting beam, taken on line yy of Fig. 1. Fig. 7 is a detail vertical sectional view through the drill-tool thrust-block and connected parts, and Fig. 8 is a bottom plan view of the drill-tool thrust-block.

In carrying out my invention I employ angular elongated base members $A A'$, having on their inner sides undercut guideways $B B'$,

adapted to receive the T-shaped cross-head C on the under side of a suitable block D . The base members $A A'$ are respectively constructed with outwardly and downwardly inclined sides $A^2 A^3$, extending from the guideways $B B'$. (See Figs. 4 and 5.)

Referring to Fig. 1 of the drawings, E indicates a suitable standard or post having an angular foot E' , through which latter passes a suitable securing-bolt E^2 . The head E^3 of this bolt is made large enough to span the space A^4 between the base members $A A'$, substantially as indicated by the dotted circle. (See Fig. 3.) The standard E is, in fact, an extension of the sliding block D ; but as illustrating one construction I show it secured thereto (see Fig. 1) by a bolt E^4 . For fixedly securing the sliding block D and the standard E to an adjustment along the base members $A A'$, I provide the latter with a series of transverse holes E^5 , adapted to receive a bolt E^6 , passing through the base members and the cross-head C of the sliding block D . (See dotted lines in Fig. 4.) The bolt E^2 is intended for two purposes—first, to provide bracing-support for the standard E , and, second, should it become necessary in using my invention to adjust the sliding block D to position on the base members $A A'$, where the bolt-holes E^5 do not register with the similar hole through the cross-head C , the nut E^7 on its upper end may be screwed down on the foot E' sufficiently tight to hold the standard against sliding movement. In connection with the base members I employ end clamps F , (see Figs. 1 and 5,) that are substantially U-shaped. These clamps have upper tightening-screws F' , that work against suitable blocks F^2 , resting on the base members (see Fig. 5) and a lower chain device F^3 . One end of this chain is fixed to the end of one leg of the clamp, and its other end is adapted for engagement with a suitable hook F^5 at the lower end of the opposite leg of the clamp. (See Fig. 5.)

In this view of the drawing G indicates a tube shaft or bolt arranged in the V-shaped recess formed by the inclined inner sides $A^2 A^3$ of the base members $A A'$. The work G , as above denoted, is held in position by the chains F^3 , adapted to be drilled. In other words, the base members of the machine are

secured to the work by the end clamp and chains, as will be described further on.

In further carrying out my invention I employ a peculiar beam H, adjustably supported on the standard E. While my invention comprehends any suitable means adapted for suitably supporting the beam H, in Figs. 1 and 2 I show one way of carrying out the idea. In these view it will be noticed that 5 the inner end of the beam H is provided with a vertical perforation I, adapted to receive the standard E. The beam H is secured against horizontal or vertical movement on the standard E by a collar J, having a binding-screw J', the collar being located below the beam, as shown in Figs. 1 and 2, and a horizontally-disposed set-screw J² in the end of the beam having its end adapted for locking engagement with the standard E, and 10 thereby hold the beam to any desired horizontal adjustment. In Fig. 1 I show a shoe J³ between the standard E and the binding end of the set-screw J². The object of the shoe J³ is simply to afford increased binding 15 effect of the set-screw on the standard.

It will be noticed that in the under side of the beam H (see Figs. 1 and 6) I provide an elongated recess K and support therein a feed-screw L, upon which is arranged an adjustable block M, conforming to the shape of the recess K. The inner end of the feed-screw L may be stepped into a socket L', (see Fig. 1,) adapted to receive lubrication through a suitable passage L². By reference to Fig. 2 it will be noticed that the outer end of the feed-screw L passes through a reduced opening L³ in the beam, and beyond which opening a socket or recess L⁴ is provided adapted to receive a collar L⁵, fixed on the feed-screw. 20 The collar L⁵ is held in the recess L⁴ by a detachable end plate L⁶. At the extreme outer end of the feed-screw L, I provide a hand-wheel L⁷. It is understood that the outer end of the feed-screw projects through a suitable opening in the end plate L⁶.

The sliding block M, hereinbefore referred to, is best shown in Figs. 6 and 7. In its preferred form it has side projections M', projecting under the beam H, which serve to prevent lateral movement of the block on the feed-screw. The side projections may be inclined downwardly to a reduced portion M² and the latter end with a lower enlarged and circular head M³. On the under side of the head M³, I arrange a rotatable thrust-block N, having in its bottom a series of depressions N². The thrust-block N is held in place by straps N³, fixed to the head M³ and formed with angular lower ends N⁴, adapted to enter a 25 groove N⁵, extending around the thrust-block, as indicated by the dotted lines in Fig. 7. The upper side of the thrust-block has a circular rack N⁶, with which a suitably-supported bevel-pinion N⁷ is adapted to engage. This 30 pinion is fixed on a stem N⁸, having an outer crank or hand-wheel N⁹. The object of the depressions N² will appear farther on.

On the upper side of the beam H, I arrange two U-shaped clamps O, adapted to be secured by opposite set-screws O'. These clamps 70 have side extensions O², with perforations adapted to receive and support elongated rods O³. (See Figs. 2 and 6.) On each rod O³, I arrange two rings O⁴, from which latter depend short lengths of chain O⁵, the use of which 75 will appear further on.

P denotes any type of pneumatic or other drill employing a feed-screw P', having an upper conical end P², adapted to enter one or the other of the depressions N² in the thrust-block 80 N. In my drawings I have shown the upper end of the feed-screw of the drill-tool in the central depression of the thrust-block N. According to my invention the drill P is supported with its upper end against the thrust-block N by a peculiar sling arrangement, which I will describe as follows: Q Q' denote two tension devices located, respectively, on opposite sides of the drill device or tool. (See Fig. 1.) Each tension device is formed with 85 upper and lower spaced bars Q², between which compression-springs Q³ are arranged. Up through the bars Q², near each end thereof, I pass a rod Q⁴, having a lower head and an upper hook Q⁶, as shown in Figs. 1 and 6. 90 The hooks afford detachable engagement with the chains O⁵. In further describing my invention reference is had to rods Q⁷, extending down through the bars Q², at the end thereof. It will be noticed that these rods are similar to the rods Q⁴, but reversely arranged—that is, their heads Q⁸ are above the upper bar Q² and their hooked ends Q⁹ below the lowermost of the two bars Q². The latter-stated rods Q⁷ pass through the compression-springs 95 Q³ between the upper and lower stated bars Q², as shown in Fig. 6.

In connection with the tension device above described I employ two side chains R R', whose links are adapted for engagement with 100 the lower hooks Q⁹, and thereby form two parallel swings which are connected by two spaced transverse chains S. It will be noticed that the parallel chains R R' and the transverse connecting-chains S are arranged 105 under the drill-tool, and when they are properly adjusted the upper end of the feed-screw P' of the drill-tool is held yieldingly against the thrust-block N.

In Fig. 1 of my drawings I show the beam 110 H and the standard E marked with degrees, the use of which will be understood.

The chief advantage with my invention over all machines known to me resides in its adaptability for drilling holes in shafting, tie-bolts, and in all similar articles or devices without removing them from their fixed position. Its conformation is such that all the parts can be constructed at minimum expense 115 adapted to the work to be done.

In use the base members are arranged on the tube bolt or rod in which a hole is to be drilled, as shown in Fig. 5, and secured thereon, according to the position of the hole to be 120

drilled, by the end clamps F and their chains F³. It is apparent that the base members may be securely affixed to the work by means of the tightening-screws F'. The drill-tool 5 being in place and supported by the sling devices, with the upper end of its feed-screw P' in the concentric depression N² of the thrust-block N, obviously it is in position to drill a vertical hole or opening into the work to 10 which the base members A A' are secured. In Fig. 1 the beam H and drill-tool are shown elevated; but it is understood that by loosening the screws J' J² the beam may be lowered on the standard E to proper height gaged by 15 the degrees marked thereon, adapting the drill-tool to the work that is to be drilled. In other words, the drill-tool is adjusted to position, with its point directly over or in the space between the two base members in position, where by simple manipulation of the feed-screw, with the drill-tool in operation, a hole can be drilled in the work to which the machine is secured. When it is desired to 20 drill a hole other than vertically, the upper end of the feed-screw P' is placed in one of the outer depressions N² in the thrust-block N. After drilling one angular hole, as just described, the thrust-block N may be rotated by the hand-wheel N⁹ and rack and pinion N⁶ 25 N⁷, thereby canting the drill-tool adapted for drilling another hole at an opposite or changed inclination. It is further apparent that my drill-tool can be adjusted along on the beam H by working the hand-wheel L⁷. 30 In making this adjustment the rings O⁴, connecting the sling device, as above described, will slide along on the side bars O³. The clamps O, that support the side bars O³, may also be adjusted by loosening the screws O'. 35 Those skilled in the art will understand that my invention is adapted for drilling holes in work other than the article or thing to which the base members are secured. The beam H may be turned upside down and the 40 drill-tool be supported uppermost, adapted for working overhead. It can be swung side- 45 wise on the standard E and secured or locked to the adjusted position by the end screw J².

With my invention a series of spaced holes 50 may be drilled without the necessity of measurement. My peculiar sling arrangement, constructed as hereinbefore described, provides adjustability of parts, whereby large or small drill-tools may be employed. The tension-springs 55 securely hold the upper end of the drill-tool against its thrust-block and at the same time allow the drill to be fed down by its feed-screw P'. The tension-springs also act upon turning the feed-screw of the 60 drill-tool backward to withdraw its bit out of the drilled hole.

Having thus described my invention, what I claim as new, and desire to secure by Letters Patent, is—

65 1. In a drilling-machine of the character described, divided base members having inner

inclined sides, and clamps on the said base members adapted for securing them to the work being drilled, substantially as described.

2. In combination with a drilling-machine 70 of the character described, base members consisting of two angular bars having their under or inner sides shaped to form a substantially and enlarged V-shaped space between them and also an upper reduced space, guide-slots 75 on the inner sides of the said base members, an adjustable block having a cross-head arranged in the said guide-slots, means for securing the said base members together, and means adapting the base members to be fixedly located, substantially as described.

3. In a drilling-machine of the character described, elongated divided base members, U-shaped clamps resting on the said base members and adapted to be tightened, and 85 means extending under the base members whereby the lower ends of the clamp are connected, substantially as described.

4. In a drilling-machine of the character described, spaced base members formed to 90 provide an under substantially V-shaped recess, adjustable U-shaped clamps, resting on the base members, having tightening means and a coupling-chain extending from end to end of the clamps, a sliding block arranged 95 between the base members and means whereby said block may be fixedly secured, a standard having fixed support on the sliding block, a foot-piece on said standard, and a bolt having adjustable connection with the base 100 members, extending up through the said foot-piece, providing securing means therefor, substantially as described.

5. In a drilling-machine of the character described, and in combination, a beam with 105 means for supporting it, a drill provided with a head, a thrust-block on the said beam provided with means for holding the drill-head in a plurality of positions, whereby the drill may be shifted relative to the thrust-block, 110 and a yielding sling adapted to support the drill in contact with the said thrust-block, substantially as described.

6. In a drilling-machine of the character described, and in combination, a beam with 115 means for supporting it, a drill provided with a head, a thrust-block on the said beam provided with means for holding the drill-head in a plurality of positions, whereby the drill may be shifted relative to the thrust-block, 120 a sling adapted to support the said drill, consisting of parallel side members extending under the drill and secured together by transverse connections, yielding sections in the said side members, and means whereby the 125 said side members are suspended from the beam, substantially as described.

7. In a drilling-machine of the character described, and in combination, a beam with means for supporting it, a rotatable thrust-block on the said beam with means for rotating it, and means for supporting the drill-

head off center, a drill-tool, and a yielding sling adapted to support the said drill-tool, substantially as described.

8. In a drilling-machine of the character described, and in combination, a beam with means for supporting it, a feed-screw on the said beam, a thrust-block on the said feed-screw, having means for supporting the drill-

head off center, a drill-tool, and a yielding sling adapted to support the said drill-tool in contact with the said thrust-block, substantially as described.
